UNITED STATES PATENT OFFICE.

JOSEPH EVERETT BERRY, OF CARTHAGE, MISSOURI.

CLOTH-CLAMP.

1,392,552.

Specification of Letters Patent.

Patented Oct. 4, 1921.

Application filed July 13, 1920. Serial No. 396,032.

To all whom it may concern:

Be it known that I, JOSEPH EVERETT BERRY, a citizen of the United States, residing at Carthage, in the county of Jasper and State 5 of Missouri, have invented a new and useful Cloth-Clamp, of which the following is a specification.

This invention relates to a clamp designed to hold the ends of cloth firmly while it is 10 being stretched on a table, bolt at a time, preparatory to cutting.

One of the objects of the invention is to provide a clamp which will hold efficiently a few thicknesses of cloth or a number of 15 thicknesses so that a number of parts can be cut at one time.

A still further object is to provide simple means whereby the connection between the clamping member and its operating means 20 can be quickly changed so as to adjust the apparatus for use in connection with either a thick pile of cloth or a thin pile.

A still further object is to provide a clamping device which can be quickly applied and 25 released and leave the top of the table free from incumbrance and which device, when placed in position, will automatically set the operating mechanism so as to exert the proper leverage.

With the foregoing and other objects in view, which will appear as the description proceeds, the invention resides in the combination and arrangement of parts and in the details of construction hereinafter 30 described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a side elevation of a portion of a cutting table having the present improvements combined therewith, a portion of one 45 of the arms of the clamp being broken away.

Fig. 2 is an end elevation of the structure shown in Fig. 1.

Referring to the figures by characters of 50 reference 1 designates the top of a cutting table mounted on supports 2 and supplemental supports or standards 3 and 4.

Swiveled in side strips 5 extending downwardly from the sides of the table near the 55 supports 2 are the stems 6 of guiding eyes or loops 7. In these loops are slidably

mounted arms 8 secured to the ends of a clamping bar 9. This bar has its lower surface covered with felt or other suitable soft material indicated at 10 and a handle 11 is 60 secured on top of the bar preferably at the center thereof.

The lower ends of the arms 8 are secured to the ends of a cross bar 12 which extends under the table and between the supports 65 2 and 3.

Extending downwardly from the end of the table is a guide loop 13 one side of which is provided with ratchet teeth, as indicated 70 at 14. A lever 15 extends through the loop 13 and is fulcrumed, at 16, upon the rear support 4. The front end of the lever has a handle 17 and extending laterally from the lever is a lip 18 adapted to engage any one of the teeth 14.

The rear end of the rear or short arm of the lever 15 is connected by a link 19 to the rear end of the rear or long arm of a lever 20 which is fulcrumed as at 21 upon the support 3. The front end of this lever 20 has 80 an enlargement 22 adapted to overhang the bar 12 and pivotally connected to this enlargement is a spacing block 23. A spring 24 connects the rear end of the lever 20 to the base of the support 4 and serves normally to hold the two levers positioned with the handle 17 elevated.

When it is desired to use this device the handle 11 is pulled upwardly so as to lift the clamping bar 9 away from the table 1. 90 The said bar is then swung forwardly past the end of the table, thereby supporting the bar 12 in a vertical plane extending back of the block 23. The ends of the cloth to be spread are then laid on the end of the table 95 1. The operator then takes hold of the handle 11 and brings the clamping bar 9 back over the table and allows the bar to rest upon the cloth. This operation is repeated until the cloth reaches a given height. If 100 there are not many thicknesses of cloth this movement will allow the bar 12 to swing forwardly under the block 25 and by then pushing downwardly on the handle 17 the levers will thrust through the block 23 against 105 the bar 12 and cause the clamp 9 to bind tightly on the fabric. The parts can be held by placing the lip 18 into engagement with one of the teeth 14.

Should there be a number of thicknesses 110 of cloth on the table 1 the same operation is repeated only, when the bar 9 is swung back-

wardly into position on the table 1 so as to bear downwardly on the cloth, the bar 12 will swing forwardly against the block 23 and cause it to swing out of spacing position. Thus when the handle 17 is thrust downwardly the enlarged end 22 of the lever 20 will come against the bar 12 instead of the spacing block 23. By providing this spacing block, however, practically the same range of movement is permitted by the handle 17 during the clamping operation whether the clamp 9 is acting upon a thick pile of material or a thin pile.

It will of course be understood that as soon as the clamping operation is completed and the material has been cut, the parts will be returned automatically to their elevated positions by the spring 24, it being necessary, of course, first to shift the lever 15 laterally to disengage the lip 18 from the teeth 14. By providing the felt pad 10 any slight unevenness in the top of the table will be taken care of.

What is claimed is:

1. The combination with a cutting table, of a clamping member tiltably and slidably connected thereto and including a clamping bar and a cross bar, a lever overhanging the cross bar, means for actuating said lever, and a spacing block pivotally connected to the lever and movable to position between the lever and the cross bar.

2. The combination with a cutting table, of a clamping member pivotally and slidably connected thereto, said member including a clamping bar extending across the table and a cross bar extending transversely under the table, a lever overhanging the cross bar, means for actuating the lever to bind the clamping bar upon material on the table, means for locking said lever against return movement, and a spacing block pivotally connected to the lever and movable to position between said lever and the cross bar.

3. The combination with a cutting table, of a lever arranged thereunder, a spacing block pivotally connected to and depending

from the lever, means for actuating said lever, a clamping bar, a cross bar, slidably and pivotal connections between the clamping and cross bars, said cross bar being movable, at one elevation, against the spacing block for engagement by the lever and, at another elevation, into position under the cross block for engagement by said block.

4. The combination with a cutting table, of guide loops swiveled at the sides thereof, arms slidably mounted within and revoluble with the loops, a clamping bar connecting the arms at one end, a cross bar connecting the arms at the other end, an operating lever, and means, including a spacing block, for transmitting motion from said operating lever to the cross bar to shift the clamping bar toward the table, said spacing block being movable into and out of operative position relative to the cross bar.

5. The combination with a cutting table and guide members swiveled at the sides thereof, of a clamping structure slidable within and movable with said guide members, said structure including a clamping bar extending transversely over the table and a cross bar extending transversely under the table, an operating lever, a power transmitting lever connected thereto, a block pivotally connected to and normally depending from the power transmitting lever, said block being movable by gravity to position above the cross bar when the clamping bar is in lowermost position, means for swinging the clamping structure to bring the transverse bar against the block to shift said block out of the path thereof when the clamping bar is in uppermost position, and means for holding the operating lever against movement in one direction.

In testimony that I claim the foregoing as my own, I have hereto affixed my signature in the presence of two witnesses.

JOSEPH EVERETT BERRY.
